ROTARY WING AIRCRAFT

Peter J. Papadakos, New York, N. Y., assignor to
Gyrodyne Company of America, Inc., Flower-
field, N. Y., a corporation of New York

Application September 2, 1953, Serial No. 26,668

Term of patent 14 years

(Cl. D71—1)

To all whom it may concern:

Be it known that I, Peter J. Papadakos, a citizen of the United States of America, residing at New York, county of Kings, State of New York, have invented a new, original, and ornamental Design for a Rotary Wing Aircraft, of which the following is a specification, reference being had to the accompanying drawings, forming part thereof.

In said drawings:

Fig. 1 is a front perspective of a rotary wing aircraft, showing my new design.

Fig. 2 is a side perspective of the same, the side of the rotary wing aircraft not shown being substantially like the side shown in this figure.

I claim:

The ornamental design for a rotary wing aircraft, as shown and described.
